TIPPING CAP

Martin Newman, Los Angeles, Calif., assignor to Glamour Industries, Inc., North Hollywood, Calif.

Filed May 9, 1975, Ser. No. 576,044

Term of patent 14 years

Int. Cl. D2—03

U.S. Cl. D2—257

Fig. 1

Fig. 2

FIG. 1 is a perspective view of a tipping cap showing my new design; and

FIG. 2 is a bottom elevation view thereof.

The side opposite to that shown in FIG. 1 is substantially similar to that shown in FIG. 1.

I claim:

The ornamental design for a tipping cap, substantially as shown and described.
